CLAIM

I claim the ornamental design for a nebulizer, as shown and described.

DESCRIPTION

FIG. 1 is a right front side perspective view of the nebulizer; FIG. 2 is a front view of the design shown in FIG. 1;

FIG. 3 is a back view of the design shown in FIG. 1; and, FIG. 4 is a right front side perspective view of the design shown in FIG. 1.

Any surfaces of the design not shown, including interior or bottom surfaces, form no part of the claimed invention.
